CLAIM

The ornamental design for a massage shoulder strap as shown and described.

DESCRIPTION

FIG. 1 is a front, right, top perspective view of a massage shoulder strap showing my new design;

FIG. 2 is a front view thereof;

FIG. 3 is a back view thereof;

FIG. 4 is an enlarged left view thereof;

FIG. 5 is an enlarged right view thereof;

FIG. 6 is a bottom view thereof;

FIG. 7 is a top view thereof;

FIG. 8 is an enlarged view of the encircled area 8 of FIG. 1;

FIG. 9 is an enlarged view of the encircled area 9 of FIG. 3;

FIG. 10 is an enlarged view of the encircled area 10 of FIG. 6; and,

FIG. 11 is an enlarged view of the encircled area 11 of FIG. 6.

The broken lines shown on the drawings depict portions of the massage shoulder strap that form no part of the claimed design. The dot-dash lines depict the enlarged view boundaries that do not form part of the claimed design.
